CLAIM

The ornamental design for a reader-writer, as shown and described.

DESCRIPTION

FIG. 1 is a perspective view of a reader-writer;

FIG. 2 is a front view thereof;

FIG. 3 is a rear view thereof;

FIG. 4 is a top plan view thereof;

FIG. 5 is a left side view thereof;

FIG. 6 is a right side view thereof;

FIG. 7 is a bottom plan view thereof; and,

FIG. 8 is a perspective view thereof in use.

The evenly spaced broken lines depict portions of the reader-writer that form no part of the claimed design.
